UNITED STATES PATENT OFFICE.

WILLIAM E. SHORE, OF WEST NEW BRIGHTON, NEW YORK.

ROTARY COMPRESSOR.

Application filed January 10, 1927. Serial No. 160,194.

The principal objects of the invention are, to devise a small and very compact high duty compressor which will have an extremely high volume of discharge and may be operated at very high speed to produce high pressure and high temperature of discharge, particularly adapted for use in preparing oil fuel for combustion.

The principal features of the invention consist in the novel construction and arrangement of a pair of pump cylinders each having an eccentric rotor therein and an impeller vane comprising a rigid unit operating in balanced and sealed arrangement in both of said cylinders, said vanes rotating about changing axes and maintaining constant contact with the cylinder surface, each rotor supporting the vane in the adjacent cylinder so as to eliminate destructive end thrust and maintaining constant contact of both ends of the vane with its cylinder wall.

In the drawings, Figure 1 is a longitudinal mid-sectional view taken through the casing of my improved double cylinder pump, the rotor and impeller vane being shown in elevation.

Figure 2 is a part cross sectional view through the pump on the line 2—2 of Figure 1.

Figure 3 is a diagram illustrating the peculiar shape of the cylinder chambers and the path of movement of the impeller vanes.

In the construction of the pump herein shown, the cylinder casing 1 is open at one side and is provided with a flange 2 and adjacent to the bearing end 3 is provided with a cylindrical recess 4 concentric with the axis of the bearing. A rotor 5 rigidly secured to the shaft 6 is provided with a cylindrical portion 7 journalled in the recess 4. The main portion of the rotor arranged eccentrically within the cylinder chamber engages the division wall 8 which separates the intake from the discharge side and it is formed with a diametrically arranged parallel faced slot 8' to receive the impeller vane 10. Recesses 9 are arranged each side of the division wall communicating with the eccentric cylinder chamber.

The cylinder cavity is of a peculiar formation, the transverse axis A through the centre of the division wall 8 being arranged in alignment with the axis of the rotor 5, the rotor axis being offset laterally from the centre 55 of the cylinder so that the periphery of the

rotor engages the division wall at one side but is spaced from the cylinder wall forming a crescent-shaped cylinder chamber.

The diameter of the cylinder perpendicular to the transverse axis A—A is greater than the diameter through said transverse axis and the walls are therefore eccentric each side of the transverse axis. This eccentricity is provided to accommodate the impeller vane 10. This vane has a maximum length substantially equal to but a trifle less than the minimum diameter of the cylinder on the transverse axis A—A, which as the rotor rotates, moves about a constantly changing axis.

The peculiarities of the construction of the cylinder are fully described in my co-pending application, Serial No. 160,193 filed January 10, 1927, for rotary compressors which illustrates the single cylinder construction. The present invention constitutes a double cylinder construction and a cylinder casing 11 similar to the casing 1 is provided with a flange 12 which abuts the flange 2. Countersunk recesses 2' and 12' are arranged in the abutting faces of the flanges 2 and 12 and within the recess thus formed is secured a ring 13 which forms a partition wall interposed between and engaging the adjacent inward end faces of the rotor and closes the outer end of the cylinder chamber 1' in the cylinder casing 1 and also the chamber 11' in the cylinder casing 11.

A rotor 14 arranged within the cylinder chamber 11' is formed with an annular flange 15 which journals in the partition ring 13 to centralize the rotor 14. The rotor 14 is arranged in diametrically opposite eccentric relation to the rotor 5 and an impeller vane 16 similar to the impeller vane 10 is slidable in the transverse slot 17 therein.

The impeller vanes 10 and 16 are arranged in right angular relation to each other and are rigidly connected together in a unitary structure by a disc 18, which forms a part thereof. This disc is free to oscillate in the space inside of the inner flange 15 of the rotor 14.

It will be seen that in a pump constructed as described, the rotor 5 propels the vane 10 in the cylinder chamber 1' and as it rotates it draws in through the intake x and discharges from the discharge y . The rotor 14 which has its transverse slot in which the impeller vane 16 slides arranged at right angles to the impeller vane 10 supports the impeller vane 10 centrally in relation to the cylinder cham-

ber 1', thus preventing the vane from throwing to either one side or the other and eliminating end thrust and the consequent wear of the cylinder and the end of the vane and thus maintaining constant contact with the cylinder at both ends of the vane.

As the blades are integrally connected, the movement of the vane 10 carries the vane 16 with it and the disc 18 carries the rotor 14 around within the cylinder 11. The vane 16 is centralized in relation to its cylinder by the vane 10, consequently each vane centralizes the other and the action of centrifugal force is controlled.

15 It will be understood from this description that the working parts are reduced to the very minimum and there is no unnecessary loss in friction in a high speed device, as each rotor functions in regard to the pumping action 20 and also acts as a centralizer for the impeller vane of the adjacent cylinder.

In the drawings I have shown the rotor 14 provided with a cylindrical extension 19 similar to the extension 7 of the rotor 5 and a bearing shaft 20 is also shown but these may, if desired, be eliminated.

The diagrammatic illustration in Figure 3 shows the eccentric formation of the cylinder walls in exaggerated form. It will be seen 30 on reference to this diagram that if a line C—C is drawn through the longitudinal axis of the rotor 5 perpendicular to the line A—A and of the same length, the ends of the line C—C would extend beyond the circle X. It 35 will be noted that the centre B of the cylinder and the centre D of the rotor are transversely in line and that a line drawn through said centres will be the true diameter of the circle described about B but if the line is caused to 40 move about the centre D and must remain the same length, then the moment that the rotor rotates to swing the line A—A out of the vertical, on account of the difference in 45 centres between the cylinder and the rotor the ends of the line if retained in balanced arrangement at either side must extend beyond the cylinder circle, first in increasing ratio 50 which reaches the maximum when the line is in the position C—C. It then reduces and 55 draws inwardly until it again merges into the true circle on the vertical axis A—A. The line C—C indicates the position of the centre line of the blade when said blade is perpendicular to the line that cuts both cylinder and rotor centre but other lines E—E and F—F are shown at 45° angles merely to illustrate the centre line of the blade at different points.

The pump thus described may be operated with the cylinders inter-connected to stage the 60 compression, that is, the discharge from one cylinder may be connected with the intake of the other or the cylinders can be operated independently.

On account of the practically perfect balancing of the impeller vanes, friction and

wear from centrifugal force is overcome in a perfectly manner and a very efficient pump is produced.

It will be understood that the terms "contact", "constant contact", or similar expressions in the foregoing specification and appended claims do not mean an actual metal-to-metal contact between the ends of the vanes and the inner surfaces of the respective cylinders, but simply that the ends of the vanes 75 are so close to the surfaces of the respective cylinders as to effect a sealing or operating contact with such surfaces. Though in the specification and claims I have termed my device a "compressor", it will be understood that 80 its use does not necessarily involve the building up of any particular degree of pressure. In the expanding chamber a degree of vacuum is ordinarily present. The pressure at the outlet end of the device obviously depends 85 upon the conditions and may be greater than or equal to, or less than atmospheric pressure. The word "compressor" as herein used is to be so understood.

What I claim as my invention is:

1. A rotary compressor comprising a pair 90 of pump cylinders arranged in eccentric relation the one to the other each being open at one end and having their open ends connected together, rotors eccentrically mounted 95 in each of said cylinders in diametrically opposite relation the one to the other and each having a transverse slot extending axially therethrough, a ring secured between the adjacent ends of said cylinders and engaging the 100 adjacent end faces of said rotors and closing the adjacent ends of each of the chambers formed between said rotors and their respective cylinders, and a pair of impeller vanes rigidly connected in right angular relation 105 to each other and slidably arranged in the transverse slots in said rotors, the adjacent edges of said vanes engaging the opposite faces of said ring, each of said rotors supporting the impeller vane in the other rotor 110 in constant contact at both ends with its cylinder wall free from end thrust.

2. A rotary compressor, comprising a pair 115 of cylinder casings each open at one end and secured together at their open ends with their axes offset, rotors formed of a pair of solid circular members mounted eccentrically in said cylinders and each having a transverse slot extending axially therethrough, an annular flange secured between the ends of said 120 cylinders and engaging in constant contact with the end surfaces of the solid circular end faces of said rotors and separating the chambers of said cylinders, and a pair of flat vanes rigidly connected and arranged at right angles to each other and slidably engaging the walls of the slots in said rotors, the adjacent edges of said vanes engaging the annular flange separating said rotors.

3. A rotary compressor, comprising a pair 130

- of cylinders each open at one end and having the open ends connected together with the cylinder axes offset, an annular flange secured between said cylinders at their open 5 ends, a rotor eccentrically journalled in one of said cylinders, a rotor journalled in said annular flange and supported eccentrically in the other cylinder, transverse slots extending diametrically through each of said rotors and presenting continuous parallel faces, and an impeller vane comprising a pair of blades formed of a unitary block of material arranged at right angles to each other and each having continuous parallel faces, one 10 blade extending into the transverse slot in one rotor and the other extending into the transverse slot in the other rotor and each having continuous surface contact with the faces of the rotor slot, each of said rotors operating to support the vane of the other rotor with its ends in constant contact with the cylinder surface in the rotation of the rotor.
4. A rotary compressor, comprising a pair of cylinder casings each having an intake 25 chamber and a discharge chamber separated by a narrow portion of the cylinder walls, said cylinders being arranged with said intake and discharge chambers in diametrically opposite position and with their axes offset, an annular flange arranged between said cylinders, a rotor eccentrically mounted in one cylinder having its periphery engaging the cylinder wall at the narrow portion separating the intake chamber from the discharge chamber, a rotor mounted in said annular flange and eccentrically supported in the other cylinder to engage the portion dividing its discharge chamber from its intake chamber, the cylinder chambers between the
- respective rotors and cylinders being separated by said annular flange which engages the inward end faces of said rotors, each of said rotors having diametrically arranged slots extending therethrough presenting continuous parallel surfaces, and an impeller vane formed of a pair of flat blades forming a unitary part of a central disc, said vanes engaging the slots in said rotor in continuous surface contact across the diameter of the rotor and extending in right angular relation to each other and adapted to be supported each by the opposite rotor within their operating cylinders free from contact with their cylinder walls through centrifugal force.
5. A rotary compressor, comprising a pair of pump cylinders arranged in eccentric relation the one to the other, each being open at one end and having their opened ends connected together, rotors eccentrically mounted in each of said cylinders in diametrically opposite relation the one to the other and each having a transverse slot extending transversely through its axis, a pair of impeller vanes rigidly connected in right-angular relation to each other and slidably arranged in the transverse slots in said rotors, and a ring secured between the adjacent ends of said cylinders and closing the adjacent ends of each of the chambers and their respective cylinders, the adjacent parallel surfaces of said vanes engaging the opposite faces of said ring, each of said rotors supporting the impeller vane in the other rotor in constant contact at both ends with its cylinder wall and free from destructive end thrust thereagainst.

WILLIAM E. SHORE.
